UNITED STATES PATENT OFFICE

107,887

DESIGN FOR A SHOE

Alfred Vamos, New York, N. Y., assignor to Bancroft Walker Company, Waltham, Mass., a corporation of Massachusetts

Application June 19, 1937, Serial No. 69,927

Term of patent 3½ years

To all whom it may concern:

Be it known that I, Alfred Vamos, a citizen of the United States and a resident of New York, in the county of New York and State of New York, have invented a new, original, and ornamental Design for a Shoe, of which the following is a specification, reference being had to the accompanying drawing, forming a part thereof, in which

Fig. 1 is a view of a shoe showing my new design as seen from above, outline thereof being conventional and shown in dot and dash lines; and

Fig. 2 is a view of the shoe in side elevation.
The dominant feature of my design resides in

two sections of mesh goring located at the throat of the shoe, separated by a plain stay in the center of the throat of the shoe, and enclosed by a line of stitching running from the upper rear end of the shoe along the upper edge of the quarters, around the sections of mesh goring and back around the upper edge of the quarters to the upper rear end of the shoe. The said line of stitching is slightly spaced from the extreme edge of the upper.

I claim:

The ornamental design for a shoe substantially as shown and described.

ALFRED VAMOS.
